[57] CLAIM

The ornamental design for the “office desk”, as shown and
described.

DESCRIPTION

FIG. 1 is a perspective view of an office desk, showing my
design;

FIG. 2 is a front view thereof;

FIG. 3 is a rear view thereof;

FIG. 4 is a side view thereof, the other side being mirror-
like; and,

FIG. 5 is a perspective view thereof, taken from above.
